LUMINAIRE REFRCTOR

George P. Wakefield, Vermilion, Ohio, assignor to Wakefield Corporation, Detroit, Mich., a corporation of Michigan

Filed Jan. 26, 1966, Ser. No. 777

Term of patent 14 years

(Cl. D48—16)

FIG. 1 is a perspective view of a luminaire refractor showing my new design from one of its duplicate ends;

FIG. 2 is a transverse cross-section view taken substantially along the line 2—2, FIG. 1;

FIG. 3 is a fragmentary longitudinal cross-section view taken substantially along the line 3—3, FIG. 2;

FIG. 4 is a fragmentary bottom plan view on enlarged scale;

FIG. 5 is a further enlarged cross-section view taken substantially along the line 5—5, FIG. 4; and

FIG. 6 is a fragmentary bottom plan view as viewed upwardly in FIG. 5.

The broken line disclosure of the end plate in FIG. 1 is shown for illustrative purposes only.

I claim:

The ornamental design for a luminaire refractor, as shown and described.
